CLAIM

The ornamental design for an I.V. holder, as shown.

DESCRIPTION

FIG. 1 is a top plan view of the I.V. holder showing our new design;

FIG. 2 is a front elevational view thereof;

FIG. 3 is a rear elevational view thereof; and

FIG. 4 is a side elevational view thereof.

The bottom plan view of the I.V. holder showing our new design is identical to the top plan view of the I.V. holder.
